UNITED STATES PATENT OFFICE.

ISAAC P. DAVIS, OF SPRINGFIELD, MASSACHUSETTS, ASSIGNOR TO JEROME W. HYDE, OF SPRINGFIELD, MASSACHUSETTS.

OVERSEAMING AND BLINDSTITCHING MACHINE.

SPECIFICATION forming part of Letters Patent No. 741,465, dated October 13, 1903.

Application filed May 10, 1902. Serial No. 106,712. (No model.)

To all whom it may concern:

Be it known that I, ISAAC P. DAVIS, a citizen of the United States of America, residing at Springfield, in the county of Hampden and State of Massachusetts, have invented new and useful Improvements in Sewing-Machines, of which the following is a specification:

This invention relates to sewing-machines, and particularly to overseaming and blind-stitching machines, and is in the nature of an improvement on the construction shown and described in United States Letters Patent issued to Charles A. Dearborn on December 19, 1899, No. 639,669.

15 The object of this invention is to improve the construction of the looper mechanism of machines of the class of which the above patent is an example, and a further object is to improve the feed mechanism.

20 The object of the improvement in the looper mechanism is to provide a device of this character in which the thread-engaging end thereof shall have its longitudinally-reciprocating movements in one plane to the end 25 that the movements of the operative end of this part shall be restricted to the shortest path possible and to the end that said end of the looper-finger may be materially reduced in size and the double-pointed looper be done 30 away with.

The object of the improvement in the feed mechanism is to provide a reciprocating feed consisting of separate members operating as one piece, which members are spring-held 35 against the work, one on each side of the line of stitches, to adapt the feed mechanism to operate on a double thickness of cloth on one side and a single thickness on the other side without impairing the efficiency of the feeding mechanism as a whole, and, further, to provide improved means for readily adjusting the feed to increase or diminish it.

In the drawings forming part of this application, Figure 1 is a side elevation of a machine embodying this invention, showing the bearing of the looper-shaft in section. Fig. 2 is an elevation of the opposite side of the machine. Fig. 3 is a front elevation of the machine. Fig. 4 is a sectional view taken on line 4-4, Fig. 1, through the feeding devices. Figs. 5 and 6 are different views of the looper-

finger. Fig. 7 is an end view of the needle-bar and looper-shaft and showing the looper-finger in section, said section being taken through the flattened end of the finger.

In its general features this machine resembles the construction which forms the subject-matter of the patent to Dearborn above referred to, though in many minor points changes incidental to the improvements above referred to have been made.

The frame of the machine comprises a base *a*, at one end of which and preferably integral therewith is the vertical standard *b*, from the upper portion of one side of which there extends to the forward end of the base *a* an arm *c*, which, as shown in Fig. 3, is somewhat offset from the side of the base. The cloth-plate *d* is supported on the forward end of an arm *e*, which is hung on the standard *b* at *f* and may thus swing more or less in a vertical plane. Under the forward end of this arm *e* is a spring *g*, which presses it upward. This spring is provided with an adjusting-nut whereby its tension may be changed.

To limit the vertical adjustment of the cloth-plate *d* there is secured on the base *a* an arm *h*, the upper end of which extends horizontally over the end of another arm *i*, which is secured to the arm *e*, and there extends down through the said horizontal upper end of the arm *h* an adjusting-screw *j*, the lower end of which constitutes a stop for the arm *i* and consequently of the cloth-plate *d*. The object of this adjustment is to provide a proper contact between the cloth and a rigidly-supported presser-foot *k*, supported in the end of the arm *c* and rigidly secured thereto when the machine is in operation; but this presser-foot is adjustable vertically by means of the screw *m* when it becomes necessary to adjust the machine to operate on various thicknesses of material.

The adjustment of the presser-foot, however, is one which affects its relation only to the needle and looper-finger, the cloth-plate being adjusted according to the changes made in the position of the presser-foot and according to the thickness of the material between it and the cloth-plate *d*. The adjusting-screw *m* is supported in the end of a spring-arm *m'*,

whereby it may yield somewhat if a seam in the fabric passes under it, it having been found that a yielding cloth-plate alone is not sufficient to produce good results.

The presser-foot *k* is transversely slotted in the path of the needle, as shown in Fig. 2 and indicated by *k'*. The cloth-plate *d* is provided with an upwardly-projecting rib *n*, lying in the line of the stitching, within which is located the feed devices, said rib, as shown in Fig. 3, being of inverted-V shape and standing well above the level of the cloth-table. The sides of this rib are cut away, as shown in Figs 1 and 2, to permit the upper 5 serrated edges of the feed-plates to be moved therethrough slightly beyond the surface thereof into contact with the work, the presser-foot *k* being formed to fit over the upper edge of the rib *n*, as shown in Fig. 3, and constituting the point of resistance for the feed mechanism. These features are common in overseaming or blindstitching machines and are essential for the proper presentation of the work to the needle, and, broadly, they do 5 not constitute a part of this invention.

The feed devices on this machine are carried on the cloth-plate *d*, and they receive their operative movements by means of an eccentric *o*, (shown in Fig. 3 and in dotted 10 lines in Fig. 2,) which eccentric is operatively connected with a crank-arm *p*, on the hub of which is a slotted arm *q*, the axis of these arms being at *f*, which is the axis on which the cloth-plate swings.

Near the forward end of the arm *e* is a shaft *r*, extending transversely thereof in a bearing cast on the arm *e*. On one end of this shaft is a crank *s*, and a connecting-rod *t* extends back therefrom to the arm *q*, being secured 35 in the slot therein adjustably, whereby the throw of the feed-plates, actuated by the shaft *r*, may be adjusted by swinging the rear end of this connecting-rod toward or from the axis of the arm *q*. This adjustment is provided 40 for herein by means of a screw *u*, rotatably supported on the hub of the arm *q*, the other end of the screw having a threaded engagement with a block *v*, which is adapted to slide 45 in the slot of the arm *q* and to which block 50 the connecting-rod *t* is pivotally secured. On that end of the shaft *r* opposite to that on which the crank *s* is secured there is, as shown clearly in Fig. 1, a second crank-arm *w*, which by means of a link *x* is connected with a block 55 *y*, pivotally supported at 2 on a slide 3, which is seen in end view in Fig. 3, and has a sliding movement parallel with and close to the under side of the cloth-plate *d*. In Fig. 1 the feed mechanism is shown in full lines at the 60 end of its movement in one direction and in dotted lines at the limit of its movement in the opposite direction. By means of the connection with the block *y* and the pivotal support of the latter at the upper corner thereof, 65 as at 2, it is seen that the oscillations of the shaft *r* will impart to said block first an upwardly-swinging movement on the slide 3 and

then, together with the latter, a horizontal movement under the cloth-plate and parallel therewith. The opposite sides of the block *y* 70 are provided with vertical slots to receive the two feed-plates 4 and 5, which are shown clearly in Fig. 4. Each of these plates is provided with an elongated slot 6, oppositely located one to another, and a pin 7 extends 75 through the block *y* and into these slots, whereby the movement of these plates 4 and 5 vertically may be limited.

It is shown in the drawings that the feed-plates do not extend to the lower edge of the block *y*, but the slots in which these plates are supported stop short of that, thus providing a shoulder between which and the lower edge of the feed-plates there may be located a spring 8, whereby normally the feed-plates 85 are pressed upwardly to the limit of the movement in this direction which is permitted by the slots 6. Thus when at the beginning of the movement of the feed mechanism the block *y*, which carries these plates, is swung 90 upwardly prior to its horizontal movement the upper serrated edges of the feed-plates come to a bearing against the under side of the fabric, which is held down over the openings in the rib *n* by the presser-foot, and upon 95 such contact therewith each plate will yield vertically according to the thickness of the cloth which is interposed between it and the presser-foot, and, as in all overseaming where a single edge of fabric is being bound down to the rest of the fabric, the thickness of the material must be on one side of the rib *n* double 100 that on the other side. The necessity for this adjustability of the feed-plates is obvious.

Coming now to the needle mechanism and looper mechanism, both are operated from the driving-shaft 9 of the machine, and the needle mechanism will be first described. The needle-shaft 10 is supported in bearings 12, (shown in Fig. 1,) which are cast, respectively, on the upper part of the standard *b* and the forward end of the arm *e*. On one end of this shaft 10 is secured the needle-arm 13, and on the opposite end of the shaft is a crank 14, only the hub of which shows 115 in Figs. 1 and 2. Referring to said Fig. 1, the crank-arm in the position in which the parts are shown extends away from the observer and its extremity (in the shape of a post 15, whose position is indicated in dotted 120 lines only) passes through a ball 16, rotatably secured in the end of an arm 17, which is eccentrically mounted on the shaft 9. The rotation of this shaft therefore will impart vertically-reciprocating movements to the 125 arm 17, which by means of the crank connection through the ball-joint described will impart to the shaft 10 the requisite oscillatory movement which is necessary to move the curved needle 18 through the fabric held 130 between the presser-foot *k* and the top of the rib *n*. The needle 18, as in all machines of this class, is substantially concentric to the needle-shaft 10, and the needle-arm 13 is ad-

justably secured on the end of this shaft to provide for the proper adjustment of the needle in its relation to other parts.

The looper devices, which constitute one of the essential novel features of this invention, consist of a looper-shaft 19 and a looper-finger 20, eccentrically mounted on the end of the looper-shaft and parallel therewith. The looper-shaft runs in the rigid bearing 21, depending from the arm *c*, as shown clearly in Fig. 1. This bearing may be provided with the split bushing 22 at either end thereof, which may be screwed into the tapered end of the bearing, whereby all wear between the bushings and the looper-shaft may be taken up. This looper-shaft has two movements in its bearings, one rotative and the other endwise, which movements are imparted thereto by means of the inclined crank-stud 23, which is eccentrically supported on the end of the shaft 9 and whose axis is inclined to the plane of its rotation on the shaft 9. The degree of its eccentricity determines the endwise movement of the looper-shaft 19, and the degree of its inclination relative to the plane of its rotation determines the degree of the rocking or oscillating movement of the looper-shaft. Connection between this point 23 and the looper-shaft is in the form of a double-jointed shaft-section 24. The latter is made endwise adjustable for the purpose of adjusting the end of the looper-finger 20 relative to the needle.

In this machine the end of the looper-finger is flattened, as at 25, Figs. 5 and 6, said flattened portion terminating in a thin sharp point. For some distance back of this the cross-sectional form of the finger is that of an oval flattened on one side, the flattened side of the finger being on the same side thereof which is cut away at the point to produce the flattened end 25. The latter terminates in a shoulder 26, which serves to hold the thread close to the end of the finger when the loop is picked up. After the needle has passed through the fabric carrying the thread with it and has reached the limit of its movement in that direction (which position is shown in Fig. 3) it begins its retrograde movement, which latter slackens up the thread between the fabric and the eye of the needle, and at this moment the position of the looper-finger is substantially that shown in said Fig. 3, and as the looper-finger advances, picking up the loop on the flattened end 25, the needle continues its retrograde movement, during which the looper-finger crosses the path of the needle carrying the loop beyond the line of the thread drawn between the work and the needle. Reaching the end of its forward movement, the looper-finger begins its oscillatory movement, which is completed at about the time or soon after the needle has finished its retrograde movement. The needle at this point begins a new forward movement and simultaneously the looper-finger begins a rearward longitudinal

movement, the point of the needle crossing the looper-finger just prior to the moment when the shoulder 26, around which the thread is looped, traverses the path of the needle.

The rocking movement whereby the looper-finger is carried over from one side of the line of stitches to the other moves the flattened extremity thereof from the position it occupies in a horizontal plane on one side to a position in a vertical plane at the other side, the effect of which is to open the loop which passes around said flattened end. This movement, however, does not permit any slackening of the loop which passes around this flattened end and bears on the shoulder 26. As clearly shown in Fig. 7, when the looper-finger has performed this oscillatory movement across the line of stitching, it lies below the level of the work where the stitching is being done, and therefore the thread running from the upper side of the looper-finger through the work lies in a position diagonal to and upwardly-inclined to the path of the needle and in a position therefore adapted to permit the latter to pass through the loop. The position of the loop diagonal to the path of the needle is due to the fact that the beginning of the feed movement takes place just after the crossing over of the loop and just a little ahead of the retrograde movement of the looper-finger. The needle after passing through the loop which is cast off by the retrograde movement of the looper-finger continues its forward movement through the material, the cast-off loop remaining slack until another loop is picked up by the looper-finger, which operation draws the next preceding loop or stitch tight, as the resistance of the tension devices, which will be referred to later, prevents the thread from paying off through the needle.

It is highly essential to the proper operation of the machine that the loop should be forward of the thread extending from the needle to the work when the needle in its forward movement passes through the loop, and to insure this position of the thread a groove 27 is made partially around the looper-finger, both ends of which groove show in Fig. 5 and only one end of which shows in Fig. 6. This groove is in such position on the looper-finger that when the latter has moved across the stitch-line at the forward end of its stroke it will locate this groove substantially on the line of thread extending from the work back to the point of the needle, the needle at this time being at the end of its retrograde movement. Therefore, when the needle goes forward again, the thread from the needle, which at this time will partly encircle the looper-finger, is carried backward by the rearward movement of the looper-finger, and is thus prevented from being carried over the shoulder 26 when the machine is running rapidly, which displacement of thread would not carry the latter through the loop correctly.

The tension devices consist in the usual

spring-actuated friction-disks 28, which are located between the spool and the take-up. The latter is indicated by 29 and is of the usual type of a swinging lever, which at the proper time—that is, just prior to the commencement of the retrograde movement of the needle—is so swung as to take up the slack in the thread resulting from such movement. This take-up arm is operated by an eccentric 10 30 on the driving-shaft 9, having a connecting-arm 31, pivotally connected at 32 to the take-up arm.

This machine possesses the advantage of operating in perfectly straight lines in the forward and rearward movements of the looper-finger, and for that reason possesses great advantage over the construction shown in the Dearborn patent, above referred to, in that it works through a shorter path of movement, 15 20 and by reason of the operation thereof in straight lines it is found much easier to regulate the tension on the thread to produce a uniform stitch. Furthermore, the thumb and finger formation of the looper-finger is done 25 away with.

In connection with the looper-finger it is to be further noted that there is a very distinct and decided advantage in the employment of a straight looper-finger working in a plane 30 35 parallel with the fabric or cloth plate in the forward and backward movements of the finger instead of having the finger of curved form and describing a curve in such movements, as is the case with the construction shown in the Dearborn patent. The looper operating 40 45 on a straight line, such as contemplated by the present invention, does not draw off as much thread as that operating on a curve and besides positively provides a more uniform tension, which is of very great importance in a machine of this character.

The feed devices, consisting of the two separate plates independently spring-pressed against the work, possess the advantage of 45 50 55 the yielding and independent contact with the work, and these devices are readily adjustable to provide variation in the feed of the material. It may be further explained in this connection that by reason of the independent yielding movement of plates 4 and 5 in parallel planes one of said plates is permitted to yield, so as to adapt the machine to receive a double thickness of cloth on which one of said plates operates and a single thickness on which the other plate operates, this being a normal condition in overseaming.

In threading this machine thread from the bobbin 33 is taken through the guide between the tension-disks 28, thence through eyes in 60 65 the posts 34, between which the take-up lever swings, passing through an eye in the latter. From the post 34 the thread passes through suitable guides on the needle-arm, thence along the under side of the needle, and up through the eye in the latter.

Having thus described my invention, what

I claim, and desire to secure by Letters Patent of the United States, is—

1. In a sewing-machine, the combination 70 of the needle arranged to reciprocate above the cloth-plate transversely to the line of feed, a stationary guide-bearing, a looper-shaft mounted to oscillate in the bearing and also held by the latter to reciprocate in a 75 fixed plane in parallelism to the cloth-plate, said shaft carrying at one end an eccentrically-supported looper-finger, and means for actuating the looper-shaft to cause the finger to reciprocate in straight lines respectively 80 above and below the path of the needle and to rock from one side of the line of stitching to the other, substantially as set forth.

2. In a sewing-machine, the combination 85 with the cloth-plate, the feeding mechanism, and the needle arranged to reciprocate above the cloth-plate transverse to the line of feed, of a stationary horizontal guide-bearing, a looper-shaft mounted to oscillate in the bearing and also held thereby to reciprocation in a 90 fixed plane in parallelism to the cloth-plate, said shaft carrying at one end an eccentrically-supported looper-finger and provided with a flattened shouldered portion upon one 95 side of its tip, and means for actuating the shaft to cause the finger to reciprocate in straight lines respectively above and below the path of the needle, and to rock from one side of the line of stitching to the other.

3. In a sewing-machine, the combination 100 with the cloth-plate, feeding mechanism, and the needle arranged to reciprocate above the cloth-plate transversely to the line of feed, of a stationary horizontal guide-bearing, a looper-shaft mounted to oscillate in the bearing and also held thereby to reciprocation in a 105 fixed plane in parallelism to the cloth-plate, said shaft carrying at one end an eccentrically-supported looper-finger and provided with a flattened shouldered portion upon one 110 side of its tip and adjacent to and in rear of said flattened portion with a transverse groove extending partially about the same, the looper-finger being also approximately flattened throughout upon the same side as the flattened shouldered portion, and means for actuating the shaft to reciprocate and rock the 115 looper-finger.

4. In a sewing-machine, the combination 120 with suitable stitch-forming mechanism, a normally stationary yieldingly-supported presser-foot, a yieldingly-mounted ridge-forming rib engaging the work beneath the presser-foot and provided with openings in the opposite sides thereof, two independently yielding feed devices arranged to project respectively through the openings in the opposite sides of the rib, and common means for reciprocating both of said devices in both a vertical and horizontal direction.

5. In a sewing-machine, the combination 125 with the stitch-forming mechanism, of a ver-

tically-yielding cloth-plate having thereon an angular rib provided with openings in the sides thereof, a yieldingly-supported presser-foot having a cap member straddling the rib, 5 and a feeding mechanism including a vertically and horizontally movable supporting element, and a pair of independent yielding feed-plates carried by the said element and respectively working through the opposite 10 openings of the rib.

6. In a sewing-machine, the combination with suitable stitch-forming mechanism, of a vertically-yielding cloth-plate having thereon an angular rib provided in the sides with 15 openings, a yieldingly-mounted presser-foot

fitting over the rib, and feed mechanism including a horizontally-reciprocating slide, a vertically-swinging support carried by said slide, a pair of duplicate independently-yielding feed-plates carried by said support and 20 projecting respectively through the separate openings of the rib, and an operating mechanism carried by the support for the cloth-plate and having means for causing the feed-plate to move in vertical and horizontal planes, 25 substantially as set forth.
